UNITED STATES PATENT OFFICE.

CATHERINE A. GILL, OF DETROIT, MICHIGAN.

BASTING COVER FOR ROASTING PANS.

1,413,579.

Specification of Letters Patent. Patented Apr. 25, 1922.

Application filed June 9, 1921. Serial No. 476,116.

To all whom it may concern:

Be it known that I, CATHERINE A. GILL, a citizen of the United States, residing at Detroit, in the county of Wayne and State 5 of Michigan, have invented a new and useful Basting Cover for Roasting Pans, of which the following is a specification.

This invention relates to culinary utensils and particularly to covers for roasting pans.

10 The object of the invention is to provide a cover for roasting pans, which, while serving as a closure for the pan to prevent the escape of moisture arising in the form of steam or vapor, as from a roast of beef, fowl or the 15 like, will also function to collect and condense such moisture and to distribute the liquid condensation in the form of drops uniformly over the surface of the roast, as in the practice of "basting" to prevent burning 20 or drying out with consequent loss of the nutritious contents.

In attaining this object the invention contemplates forming the cover, which is preferably oval in shape, by stamping the body 25 and end or head integrally from a single sheet of metal, said head being depressed or concaved centrally within the body and having struck upon the inner face thereof a plurality of depending ribs radially extending from a central area to a peripheral margin of said head. Within said central area there is also depressed a plurality of 30 semi-spherical knobs distributed and disposed to adjoin the terminals of one or more of said ribs, and which are adapted to serve as dripping points from which the liquid condensation conducted thereto by said ribs is discharged upon the surface of a roast 35 enclosed beneath said cover.

40 A preferred embodiment of the invention is illustrated in the accompanying drawings, wherein,

Fig. 1 is a plan view of the improved cover.

45 Fig. 2 is a central longitudinal vertical sectional view of the same.

Fig. 3 is a view of the cover in central transverse section.

As is usual with articles of this character, 50 the improved cover is formed of sheet metal substantially elliptical in shape and comprises the top or head 1 and deep marginal flange or body 2. Said body at its lower edge is return-bent and projected slightly 55 outwardly as indicated at 3 to form a seat to engage the pan as indicated by dotted

lines in Fig. 2. The top 1 of the cover is slightly dished or concaved and is provided with a considerable number of ribs 4 upon its under surface, which may be formed by indenting the upper face of said cover, said ribs being spaced and distributed to radiate from a central to the peripheral portion of the top. At the inner ends of said ribs, conical depressions or semi-spherical knobs 5 are formed, the same being symmetrically distributed throughout the central portion of the cover. The function of said ribs is to conduct the drops of liquid condensing and gathering upon the top 1 to the center portion of the cover, the inclination of the ribs resulting from the dished formation of the top tending to produce the desired flow. The knobs 5 function as dripping points from which the condensed liquid is precipitated upon the roast (not shown) beneath the cover, said knobs having a depth somewhat greater than that of the ribs 4, so as to receive the drops of liquid guided by the ribs and to establish definite dripping points. 80

A roaster provided with a cover constructed as above described is rendered self-basting, the basting being accomplished by the liquid condensing upon the top 1, flowing on the ribs 4 and dripping from the knobs 5. Because of the uniform distribution of these ribs and knobs throughout the central portion of the top, the condensed liquid is caused to drip upon the entire central portion of the roast so as to flow thereover and 90 maintain the surface of the same continually moistened, and thus prevent drying out of the nutritious juices.

It is a desirable feature of the described construction that it is not necessary to maintain the roasting pan and its cover accurately leveled to insure proper functioning of the cover to effect basting. A slight inclination of the pan and cover will not be sufficient to counteract the guiding inclination 100 of the ribs 4, resulting from the dished formation of the top 1.

What I claim is:

1. A roasting pan cover having a dished top, formed with a plurality of ribs upon 105 its under surface radiating from a central portion of said top and formed at the inner ends of said ribs with knobs of greater depth than the ribs.

2. A roasting pan cover having a plurality 110 of knobs upon its under face substantially throughout its central portion, and having

projections for guiding condensed vapor to said knobs from the area of the top surrounding said central portion.

3. A roasting pan cover having a dished top and a plurality of depending knobs distributed upon the central portion of the under face of said top, said knobs forming

dripping points for condensed liquid, and means for guiding the condensed liquid from the surrounding portion of the top to 10 said dripping points.

In testimony whereof I sign this specification.

CATHERINE A. GILL.
